UNITED STATES PATENT OFFICE.

CHARLES R. MURRAY, OF CHICAGO, ILLINOIS.

DESIGN FOR A TYPE-SPACE.

SPECIFICATION forming part of Design No. 29,311, dated September 6, 1898.

Application filed February 24, 1898. Serial No. 671,535. Term of patent 14 years.

To all whom it may concern:

Be it known that I, CHARLES R. MURRAY, a citizen of the United States, residing at Chicago, county of Cook, and State of Illinois, 5 have invented and produced a certain new, useful, and original Shape of Type-Space, which is fully set forth in the following specification, reference being had to the accompanying drawings, forming a part thereof.

- o This invention is a design for a type-space and is characterized by the longitudinal outline in the plane of the runningwise dimension of such space, said outline being serpentine between end portions, which are straight 5 and which have their lateral surfaces at one side in the plane of the crests or nodes of the intermediate inflections at that side.

In the drawings, Figure 1 is a greatly-enlarged edge elevation of my design for type-space. Fig. 2 is a perspective view of the

same on a smaller scale than Fig. 1, but still enlarged beyond type size.

A' A' A' are the crests of the serpentine inflections of longitudinal outline at one side; A² A², the crests of such inflections at the opposite sides. 25

A³ A³ are the straight portions referred to at the ends, and A³⁰ A³⁰ are their faces, which stand in the plane of the crests or nodes A² A² at that side. 30

I claim—

The design for a type-space herein shown and described.

In testimony whereof I have hereunto set my hand, in the presence of two witnesses, 35 at Chicago, this 19th day of February, 1898.

CHAS. R. MURRAY.

Witnesses:

CHAS. S. BURTON,
JEAN ELLIOTT.
